[57] ABSTRACT

In a soaking furnace for heating metal parts, a burner works at full power during a heating-up period and at reduced power during a soaking period. Combustion gases are fed into the furnace with such velocity that the resulting turbulence causes uniform temperature distribution. When the burner is operated at reduced power, the total amount of fuel and air supplied is reduced but the speed of admission to the furnace is increased to maintain turbulence and uniform temperature distribution. The burner includes two concentric parts connected separately to common fuel air manifolds so that one part may be switched off thereby causing higher rate of flow to the other burner part.

**METHOD OF HEATING STEEL INGOTS SOAKING
PITS AND COMBUSTION SYSTEM FOR
PERFORMING SAID METHOD**

BACKGROUND OF THE INVENTION

The invention relates to a method of heating metal parts, particularly steel ingots or the like in soaking furnaces, particularly pit type furnaces, in which the furnace space is heated with the aid of a burner arrangement by the supply of fuel and air for combustion in suitably regulated proportions. In such methods the most uniform possible temperature distribution in the furnace space may be achieved through intensive turbulence of the combustion gases, and the heating operation may consist of a heating-up period, in which the burner arrangement works at high heating rate and of a soaking period which follows and in which the burner arrangement works at reduced heating rate through the reduction of the total amount of fuel and air for combustion supplied, while retaining the same fuel to air ratio. The invention also relates to burner arrangements for carrying out such methods.

The problem underlying the invention consists in developing a method of this kind which reduces the total heating time, permits economical operation of the soaking or pit type furnace, and in conjunction with a general increase in output of the furnace plant provides uniform soaking of the furnace charge to the desired final temperature, for example rolling temperature, with the greatest possible accuracy.

SUMMARY OF THE INVENTION

According to the invention this problem is solved by heating the furnace space walls during the heating-up period to a temperature which is higher than the highest permissible surface temperature of the furnace charge, while at least in the starting portion of the following soaking period the speed of admission of the fuel and air for combustion into the furnace chamber is increased to such an extent that the turbulence and uniformity of distribution of the combustion gases in the furnace space at least remain unchanged or are increased.

In the method according to the invention the furnace walls are thus first, that is to say in the heating-up period with the burner arrangement working at high or full power, heated to a temperature which is higher than the maximum permissible surface temperature of the furnace charge, that is to say than the temperature at which for example the surfaces of the steel ingots begin to melt. Heat at high temperature is thus stored in the furnace space walls, while at the same time the still relatively cold furnace charge is heated rapidly and effectively by the hot combustion gases. The burner arrangement is so constructed and designed, or is operated in such a manner, that in the entire furnace space the most uniform possible temperature distribution is achieved, particularly through intensive turbulence of the combustion gases. The ratio of fuel to combustion air has a determined favorable value adapted to requirements in each particular case. In the following soaking period the power of the burner arrangement is reduced by throttling the total amount of fuel and air for combustion supplied, while retaining the same ratio of fuel to air for combustion. Thus on the one hand the heat supplied by the burner arrangement and on the

other hand the volume of combustion gases produced are correspondingly reduced. Consequently the furnace space walls, which were superheated during the heating-up period to a higher temperature than the maximum permissible surface temperature of the furnace charge, now give up their stored heat to the furnace charge and thereby provide the heat still required for the soaking of the furnace charge even though the power of the burner arrangement is now throttled. At the same time the speed of admission of the fuel and air for combustion entering the furnace space is increased to such an extent that the turbulence of the hot combustion gases is retained practically unchanged as in the heating-up period, or possibly even increased, even though the volume of combustion gases has now been reduced. Despite the reduced power of the burner arrangement, the same most uniform possible temperature distribution is thus on the one hand retained in the entire furnace space, while on the other hand the transmission to the furnace charge of the heat stored in the furnace space walls is assisted, accelerated, and made uniform, since the transfer of heat is also, or mainly, effected by convection and not solely by pure radiation. As a final result, very rapid and uniform heating of the furnace charge, in conjunction with particularly economical operation of the burner arrangement or of the furnace plant, is achieved.

Any desired gaseous fuel, for example generator gas, blast furnace gas, coke oven gas, and the like, or any desired liquid or solid fuel, which however must be capable of being brought into a gaseous or gas-like condition, for example an atomized or gasified liquid fuel or a mixture of pulverized coal and air, or the like, may be used as fuel for carrying out the method according to the invention.

The speed of admission of the fuel and air for combustion into the furnace space may have any desired absolute value both during the heating-up period and in the soaking period. The only important thing is that this speed of admission, in conjunction with the construction or design of the burner arrangement, should ensure the greatest possible turbulence and the most uniform distribution of the combustion gases in the furnace space during the heating-up period with the burner arrangement operating at full power, and that in the following soaking period, with the burner operation operating at reduced power, this speed should be increased to such an extent that in consequence of the correspondingly higher turbulence of the combustion gases, at least the same uniform distribution of the combustion gases is maintained.

For the purpose of carrying out the method, the invention provides a burner arrangement which is characterized by at least two burners, each with a fuel supply pipe and an air supply pipe, and also by control means, controlled automatically in dependence on the temperature in the furnace space, for throttling the fuel and air supply pipes of one burner and simultaneously correspondingly increasing the pressure in the fuel and air supply pipes of the other burner, at least in the initial portion of the soaking period, while the ratio of the fuel to air for combustion remains constant for both burners. In the heating-up period both burners may work practically with full power, the total amount of fuel and air for combustion supplied to the two burners

corresponding to heat requirements for heating the furnace space walls to a predetermined maximum temperature which is higher than the maximum permissible surface temperature of the furnace charge. The pressure in the fuel and air supply pipes for both burners, and consequently also the speed of admission of the fuel and air for combustion into the furnace space, which is dependent thereon, are so high that the turbulence of the combustion gases in the furnace space ensures the desired uniform temperature distribution. After the maximum temperature of the furnace space walls has been reached, the fuel and air supply pipes of one burner are automatically throttled progressively by the control means responding to the furnace space temperature, until the burner in question is completely disconnected or stopped. The entire amount of fuel and air for combustion introduced into the furnace space, and consequently both the heat supplied and the volume of the combustion gases produced, are thereby reduced. At the same time however the pressure in the fuel and air supply pipes of the other burner are likewise automatically increased to such an extent that the resulting higher speed of admission of the fuel and air for combustion brings about the same or greater turbulence of the combustion gases in the furnace space and maintains the same or greater uniformity of distribution of these combustion gases and consequently also of the temperature.

According to another advantageous feature of the invention the two burners are combined in a common burner head and disposed coaxially relative to each other, with concentric annular outlet nozzles for fuel and air. Through this arrangement, in conjunction with a simple, compact construction, the same spatial or geometrical conditions are retained for the formation of turbulence of the combustion gases in the furnace space both in the heating-up period when both burners are operating simultaneously and in the following soaking period when a single burner is operating.

According to another advantageous feature of the invention, the increase in pressure in the fuel and air supply pipes of one burner in dependence on the throttling of the fuel and supply pipes of the other burner can be achieved in a particularly simple manner by connecting on the one hand the fuel supply pipes and on the other hand the air supply pipes of both burners through respective fuel and air manifolds to common fuel and air blowers, while the fuel and air supply pipes of one burner are provided with simultaneously operable throttle elements. In this construction, at the end of the heating-up period only the throttle elements in the fuel and air supply pipes of one burner need be closed simultaneously, whereby the pressure in the fuel and air supply pipes of the other burner is automatically increased while the fuel and air blowers continue to run unchanged.

BRIEF DESCRIPTION OF THE DRAWINGS

FIG. 1 shows a burner arrangement for carrying out the method according to the invention, illustrated diagrammatically,

FIG. 2 is a longitudinal section of the burner head with two coaxial burners,

FIG. 3 is an elevation of the burner head, viewed from the right-hand side in FIG. 2, and

FIG. 4 shows some characteristic curves of the method according to the invention during the heating-up and soaking periods.

DESCRIPTION OF THE PREFERRED EMBODIMENT

FIG. 1 illustrates diagrammatically a pit type furnace 1 with a cover plate 101 and waste gas offtake 3 leading into a chimney 2. The pit type furnace 1 is heated with the aid of a burner arrangement which is illustrated diagrammatically in FIG. 1 and of which a preferred form of construction is shown in FIGS. 2 and 3. This burner arrangement consists of at least one burner head 4 provided in the side wall of the pit type furnace 1 and associated with two burners disposed coaxially one around the other and operated with a mixture of gaseous fuel, for example, coke oven gas and air for combustion.

20 In the example of embodiment illustrated the two burners consist of an air chamber 5 and three tubes 6, 7, and 8 disposed in said air chamber coaxially around one another and spaced radially apart. The air chamber 5 is connected on the one hand to an air supply pipe 9 and on the other hand to a ring of air outlet nozzles 10 disposed in the burner head. The air outlet nozzles 10 are inclined convergently in relation to the longitudinal axis of the burner (as shown in FIG. 2) and at the same time are also directed obliquely to the respective radial planes, so that the axes of the nozzles do not pass through the axis of the burner as can be seen in particular from FIG. 3. The outer tube 6 is joined to a fuel supply pipe 11 and leads into a central outlet aperture 12 in the burner head 4. The other two coaxial pipes 7 and 8 likewise lead into the central outlet aperture 12 of the burner head 4, the intermediate tube 7 being connected by an elbow 13 to an air supply pipe 14 and the innermost tube 8 to a fuel supply pipe 15. The air chamber 5, with the air outlet nozzles 10, and the outer fuel tube form a first, outer burner associated with the air and fuel supply pipes 9 and 11. The intermediate air tube 7 and the innermost fuel tube 8 form a second, inner burner with the associated air and fuel supply pipes 14 and 15.

45 The air supply pipes 9, 14 of both the outer burners 5, 6 and the inner burner 7, 8 are connected through an air manifold 16 to a common air blower 17, as illustrated particularly in FIG. 1. The fuel supply pipes 11 and 15 of the two burners 5, 6 and 7, 8 are likewise connected by a fuel manifold 18 to a common fuel blower 19. Throttle elements 20 and 21 respectively are provided in the air supply pipe 9 and in the fuel supply pipe 11 of the outer burner 5, 6. The air and fuel manifolds 16 and 18 respectively are likewise each provided with a throttle element 22 and 23 respectively. The throttle elements 20, 21, 22, 23 are operated by electrical adjusting motors 120, 121, 122 and 123 respectively. The adjusting motors 120 and 122 of the throttle elements 20 and 22 in the air supply pipe 9 of the outer burner 5, 6 and in the air manifold 16 associated with the two burners 5, 6 and 7, 8 are controlled by a temperature sensor 25 responding to the temperature of the inner wall of the pit furnace 1, with the aid of a thermoelectric transducer 25 and a control device 26, which is known in itself.

The suction pipes 117 and 119 of the air and fuel blowers 17 and 19 respectively each contain a flow measuring device 27 and 29 respectively, these devices being known in themselves. These measuring devices 27, 29 are each connected by a respective transducer 127 and 129 to a controller 28, which is likewise known in itself and which controls the adjusting motor 121 of the throttle element 21 in the fuel supply pipe 11 of the outer burner 5, 6 and the adjusting motor 123 of the throttle element 23 in the fuel manifold 18 associated with the two burners 5, 6 and 7, 8.

The controller 28 is constructed in a manner known in itself so that in the event of fluctuations of the flows in the suction pipes 117, 119 of the air and fuel blowers 17, 19, and particularly in the event of variations of the air flow in the suction pipe 117 of the air blower 17, it operates the throttle elements 21, 23 so as to maintain a predetermined, adjustable and readjustable fuel/air for combustion ratio in both the coaxial burners.

The method of heating metal parts, particularly steel ingots, in the pit type furnace 1, which can be carried out with the burner arrangement according to FIGS. 1 to 3, will now be described with the aid of FIG. 4. FIG. 4 shows the following characteristic curves plotted against time T:

Curve H: Pressure of fuel and air for combustion in the outer burner 5, 6, in millimeters of water column.

Curve K: Pressure of fuel and air for combustion in the inner burner 7, 8, in millimeters of water column.

Curve L: Total inflow of fuel and air for combustion in both burners 5, 6 and 7, 8 as a percentage of the total fuel and air for combustion inflow with both burners at full power.

Curve M: Temperature of combustion gases in the pit furnace space, in °C.

Curve N: Temperature of inner wall of pit furnace space, in °C. The heating-up period A extends to the point of time T1 and then the soaking period D commences. S indicates the maximum permissible surface temperature of the steel ingots, that is to say the temperature at which the surfaces of the ingots begin to melt.

At the beginning of the heating-up period A the throttle elements 20, 21 in the air and fuel supply pipes 9, 11 of the outer burner 5, 6 are open. Both burners 5, 6 and 7, 8 work at full power. The throttle elements 22 and 23 in the air and fuel manifolds 16, 18 are opened to such an extent that on the one hand the adjusted ratio of fuel to air for combustion and on the other hand the total inflow of fuel and air for combustion required for maximum power operation of both burners 5, 6 and 7, 8 are achieved. The pressure in the air and fuel manifolds 16, 18 and in the air and fuel supply pipes 9, 11 and 14, 15 branching off therefrom and feeding the two burners 5, 6 and 7, 8 respectively, is so high that the admission speed of the fuel and air for combustion entering the pit type furnace 1, which is pressure dependent, is correspondingly high and gives rise to great turbulence of the combustion gases and consequently uniform distribution of the combustion gases and of the temperature in the furnace space.

In the heating-up period A the still relatively cold steel ingots absorb heat from the hot combustion gases, while at the same time the walls of the pit type furnace 1 are heated. The heating-up period A lasts until the

walls of the pit type furnace reach a temperature N1 which is higher than the maximum permissible surface temperature S of the steel ingots. The temperature sensor 24 responds to this maximum temperature N1 of the furnace space walls and by means of the control device 26 and the adjusting motor 120 effects the gradual closing of the throttle element 20 in the air supply pipe 16 of the outer burner 5, 6. The measuring instrument 27 disposed in the suction pipe 117 of the air blower 17 responds to the reduction of air flow produced by the closing of the throttle element 20. The controller 28 consequently closes the throttle element 21, by means of the adjusting motor 121. It does this simultaneously with closure of the air throttle element 20 and maintains the required adjusted fuel/air for combustion ratio. The closing of the throttle elements 20 and 21 in the air and fuel supply pipes 9 and 11 respectively of the outer burner 5, 6 starts at the moment T1 at the end of the heating-up period A and is terminated at the moment T2 in the following soaking period D. The pressure of the air for combustion and fuel in the outer burner 5, 6 consequently gradually drops to zero in the period T1-T2, as the portion H1-H2 of curve H shows. Consequently, within this period T1-T2 the total inflow of fuel and air for combustion also drops progressively from the 100 percent value L1 corresponding to full power of both burners 5, 6 and 7, 8 to a value L2 corresponding only to full power of the inner burner 7, 8 which continues to operate. At the same time the pressure of the fuel and of the air for combustion in the inner burner 7, 8 gradually rises, as the portion K1-K2 of the curve K shows, since with increasing throttling of the air and fuel supply pipes 9, 11 of the outer burner 5, 6 the corresponding pressure losses fall off and the inner burner 7, 8 now receives the entire delivery pressure of the air and fuel blowers 17, 19. The pressure rise in the inner burner 7, 8 corresponds to an increase of the speed of admission of the air for combustion and fuel into the pit type furnace 1. This increased speed of the air for combustion and fuel feeding the inner burner 7, 8 is so great that even though the total volume of combustion gases produced is now smaller it produces approximately the same intensive turbulence of the combustion gases in the furnace 1 as in the heating-up period A, or even produces still greater turbulence and consequently, despite the reduced power of the burners, ensures uniform distribution of the combustion gases and of the temperature in the furnace space.

At the moment T1, that is to say at the end of the heating-up period, the temperature N1 of the furnace space walls is higher and the temperature M1 of the combustion gases is lower than the maximum permissible surface temperature S of the steel ingots. In consequence of the throttling of the outer burner 5, 6 and of the corresponding reduction of the supply of heat, the superheated furnace space walls now give their stored heat to the steel ingots. The maintenance of the intensive turbulence of the combustion gases in the furnace space substantially assists the transfer of heat from the furnace space walls to the steel ingots, since it causes transfer of heat through convection and not through pure radiation alone. The temperature of the combustion gases consequently rises slightly further and is stabilized at the temperature value M2, which is

still lower than the maximum permissible surface temperature S of the steel ingots. The temperature of the furnace space walls on the other hand retains its maximum value $N1$ for a relatively short time and then gradually declines.

In the soaking period D so much heat is supplied to the steel ingots, partly from the superheated furnace space walls and partly from the inner burner 7, 8 which continues to operate, that all of them attain the desired uniform final temperature, for example the prescribed rolling temperature, and at the same time are uniformly soaked. When the temperature of the steel ingots approaches the desired final temperature, that is to say approximately at the moment $T2$, the throttle element 22 in the air manifold 16 is gradually closed with the aid of the control device 26 and the adjusting motor 122. This is brought about by a control pulse of a temperature sensor, for example through the temperature sensor 24 responding to the temperature of the furnace space walls. The controller 28, which maintains unchanged the adjusted ratio of air for combustion to fuel, simultaneously closes by means of the adjusting motor 123 the throttle element 23 in the fuel manifold 18. The inflow of fuel and air for combustion drops further from the value $L2$ corresponding to the full power of the inner burner 7, 8, while at the same time the pressure of the fuel and of the air for combustion in the inner burner 7, 8 drop from the maximum value $L2$ which it had attained.

The main advantage of the method according to the invention consists in that the furnace charge, for example the steel ingots disposed in the pit type furnace 1, is heated uniformly throughout to the desired temperature in a substantially shorter time than by known methods, while the burner arrangement proposed according to the invention as being preferable for carrying out this method has a particularly simple, compact, operationally reliable, and economical construction.

The invention is naturally not restricted to the example of embodiment illustrated and described, but within the framework of the general principle of the invention various modifications are possible. In particular, other burner arrangements may be used for carrying out the method according to the invention. The burner arrangement proposed in accordance with the invention may also be modified in respect of its construction or operation. Thus, for example, at the end of the heating-up period A the inner burner 7, 8 may be throttled or put out of action and the outer burner 5, 6 kept in operation. For this purpose it is merely necessary for the throttle elements 20, 21 to be disposed in the air and fuel supply pipes 14 and 15 respectively of the inner burner 7, 8 instead of in the supply pipes 9, 11 of the outer burner.

We claim:

1. A soaking furnace including furnace walls enclosing a furnace space to contain an ingot to be treated and a burner arrangement connected thereto, comprising at least two burners, each of which is provided with a fuel supply pipe and an air supply pipe, and control means controlled automatically in dependence on the temperature in the furnace space for throttling the air and fuel supply pipes of one burner and causing simultaneous corresponding increase of pressure in the air and fuel supply pipes of the other burner at least in the

initial portion of the soaking period, the ratio of fuel to air for combustion remaining constant for both burners.

2. A burner arrangement according to claim 1, in which the two burners are combined in a common burner head and are disposed coaxially around one another with concentric annular outlet nozzles for fuel and air.

3. A burner arrangement according to claim 2, in which on the one hand the air supply pipes and on the other hand the fuel supply pipes of the two burners are each connected by an air manifold and a fuel manifold to common air and fuel blowers, and that the air and fuel supply pipes of one burner are provided with simultaneously operable throttle elements.

4. A burner arrangement according to claim 3, in which the throttle element in the air supply pipe of one burner is controlled by a control device responding to the temperature in the furnace space and the throttle element in the fuel supply pipe of the same burner is controlled by a controller maintaining an adjusted ratio of fuel to air.

5. A burner arrangement according to claim 4, in which the air and fuel manifolds common to the two burners are each provided with a throttle element downstream of the respective air and fuel blowers, and these throttle elements can be operated simultaneously while retaining the same ratio of fuel to air.

6. A burner arrangement according to claim 5, in which the throttle element in the air manifold is controlled by a control device responding to the temperature in the furnace space or to the temperature of the furnace charge, and the throttle element in the fuel manifold is controlled by a controller maintaining an adjusted ratio of fuel to air.

7. A burner arrangement according to claim 6, in which the said control device has a temperature sensor responding to the temperature of the furnace space walls.

8. A burner arrangement according to claim 7, in which the said controller for maintaining the adjusted ratio of fuel to air for combustion is provided with two measuring instruments responding to the flow and disposed in the suction pipes of the air and fuel blowers respectively.

9. A method of heating metal ingots in a soaking furnace of the type including a pair of concentric burners having separate individual fuel and air supply systems, the steps of heating the soaking furnace walls to a temperature of the maximum permissible surface temperature of the metal ingot by initially operating both burners at their maximum capacity producing an intense turbulence of the combustion gases in the furnace space, reducing the total fuel and air supplied to the burners during a soaking period while simultaneously increasing the speed of admission of the fuel and air for combustion into the furnace space to an extent such that the turbulence of the combustion gases in the furnace space does not initially decrease.

10. The method of claim 9 wherein the steps of reducing the total fuel and air supplied to the burners while simultaneously increasing the speed of admission of the fuel and air for combustion into the furnace space includes the steps of reducing the fuel and air supplied through one of said burners while simultane-

3,689,041

9

ously increasing the speed of admission of the fuel and
air through the other of said burners.
